UNITED STATES PATENT OFFICE.

ALFRED HEALD, OF PHILADELPHIA, PENNSYLVANIA, ASSIGNOR TO McCALLUM, CREASE & SLOAN, OF SAME PLACE.

DESIGN FOR A CARPET-PATTERN.

Specification forming part of Design No. 5,375, dated November 21, 1871.

To all whom it may concern:

Be it known that I, ALFRED HEALD, of Philadelphia, county of Philadelphia and State of Pennsylvania, have invented a Design for a Carpet-Pattern, of which the following is a specification:

The design in the accompanying drawing represents sufficient of a carpet-pattern to illustrate my design, the main features of which are the features A and B, each overlapped by four smaller diamond-shaped figures, C. Each member A has outer and inner borders *a* and *a'* and a central ornament, *b*, and each member B has also a central ornament, *c*, differing from that of the members A, a narrow rib, *d*, which connects the corners of the diamond-shaped figures C and foliated corner ornaments *e*. The figures C are

ornamented, as shown, and the space between the said figures and the members A and B is occupied by light ornamental figures, *h*, of a character too closely represented in the drawing to need description.

Irrespective of the colors employed,
I claim—

The design for a carpet-pattern, substantially as described, and as represented in and by the accompanying drawing.

In testimony whereof I have signed my name to this specification in the presence of two subscribing witnesses.

ALFRED HEALD.
